UNITED STATES PATENT OFFICE.

JAMES W. CAMPBELL, OF NEW YORK, N. Y.

IMPROVEMENT IN CARVING-MACHINES.

Specification forming part of Letters Patent No. 117,978, dated August 15, 1871.

To all whom it may concern:

Be it known that I, JAMES W. CAMPBELL, of the city, county, and State of New York, have invented certain new and useful Improvements in Carving-Machines, of which the following is a full, clear, and exact description, reference being had to the accompanying drawing which forms part of this specification, and in which the figures that relate to the machine are drawn to a scale of about one inch to the foot, and the figures that relate to the work done by the machine represent said work full size.

Figure 1 is a side view of a carving-machine constructed in accordance with my invention; Fig. 2, a sectional plan thereof through the line *x x* in Fig. 1; Fig. 3, a transverse section of the same through the line *y y* in Fig. 1. Fig. 4 is a side view, and Fig. 5 a top or edge view of a strip or piece of work as done by the machine.

Similar letters of reference indicate corresponding parts throughout the several figures.

This invention relates to a machine for automatically cutting or carving what is termed "rustic stem," a particular description of carved work used for picture-frames, and which, prior to the invention of this machine, has been produced by hand at a great expense of time and labor, and often very imperfectly or irregularly. The invention comprises a cutter-head which has a threefold motion, namely, a revolving one around an axis arranged at right angles or nearly so to the direction in which the wood or strip to be carved is fed through the machine, a lateral movement in direction of the length of said axis, and a vibrating or up-and-down movement relatively to the work as it passes under the cutter-head. The invention likewise includes an arrangement of revolving side cutters, having also a vibratory motion to or from the work by means of a cam or cams, in combination with a pendent support of said cutters, and a driving-belt arrangement that holds or draws them together, and that dispenses with weights or springs to keep said cutters up to action by the cam or cams. The invention also comprises various advantageous combinations of details by which these several movements are effected.

Having thus specified the nature of the invention, its description will be proceeded with in reference to the accompanying drawing:

A represents the bed or table of the machine,

on or along which the strip of wood to be carved is fed in direction of the arrow *z*, by means of a revolving feeder, B. This table should be adjustable up or down to suit different depths or thicknesses of stuff and to adapt the latter to the cutters.

Prior to describing the action of the cutters it will be well to refer to Figs. 4 and 5, which show a piece of rustic-stem work, C, the peculiarities of which, so far as it is necessary to explain the same here, consist of serpentine or spirally-arranged ridges with intervening grooves *b* formed in successive sections or lengths, separated by semi-knot holes that may be cut by a gouge after the work comes from the machine. Each of these spirally-ridged and grooved sections is hollowed out, as at *c* on top of the strip, and as at *d d* on the sides thereof. Said strip has a generally-rounded configuration given it transversely on its upper edge, and the serpentine grooves *b* and ridges formed therein or on, also the curvilinear depressions or hollows *c* made therein in direction of the length of the strip by means of a revolving cutter-head, D, provided with a cutter or cutters of the requisite shape. This cutter-head, in addition to its rotary motion, has a lateral reciprocating movement relatively to the strip, by which the serpentine disposition of the aforesaid grooves and ridges is produced, also an up-and-down motion to form the curvilinear depressions or hollows *c*.

Such threefold action of the cutters carried by the cutter-head D is effected as follows: The transversely-arranged shaft E that carries said cutter-head is continuously revolved by means of a belt, *e*, and pulleys *f g* from a main driving-shaft, F. Said shaft E has its rear bearing *v* hung by trunnions or side pivots *h h* in a box, G, which is fitted to the frame so as to be capable of sliding to and fro in a transverse direction to the machine—or in other words, in a longitudinal direction of the shaft E, which it carries during such movement along with it. This motion gives the serpentine grooving action to the cutters of the revolving cutter-head D, and is produced by the joint actions of a revolving cam, H, operating against a leg, *i*, of the sliding box G, and a spring, I, connected with said box. The cam H receives its rotary motion by a belt, *k*, from either one of two or more differently-sized pulleys, J, on the driving-shaft F, to one of two

or more differently-sized pulleys, K, on a lower cross-shaft, L, which latter, by means of a belt, *l*, and pulleys *m n*, revolves the shaft M that carries the rotary feeder B, and that, by a spur-wheel, *o*, communicates motion through a wheel, *p*, to a cross-shaft, N. This cross-shaft N has a wheel, *q*, on it, which gears with a wheel, *r*, to rotate the cam H, by which, in conjunction with the spring I, the cutter-head D is reciprocated laterally in relation to the strip. Said cross-shaft N also carries a spur-wheel, *s*, which gears with a wheel, *t*, arranged beneath the forward portion of the cutter-head shaft E, and said wheel *t* caused to rotate a cam, P, that serves to give the necessary up-and-down motion to the shaft E at its forward end to form the longitudinal upper hollows *c* in the strip. For this purpose the forward bearing Q of the shaft E is fitted by vertical V-guides, so as to be capable of rising and falling in the box which carries said bearing, the trunnions or pivots *h h* being the centers of motion, which is a vertically-vibrating or rocking one. The curvilinear hollows *d d* in the sides of the strip are produced by horizontally-revolving cutter-heads R R, provided with suitable cutters, such reductions taking place after the strip has passed from under the cutter-head D. The vertical or approximately-vertical shafts of these horizontally-revolving cutter-heads have their lower bearings *a' a'* fitted so as to be capable of sliding to and fro in a transverse relation to the strip, and their upper bearings *b' b'* attached by pivots *c' c'*, so that said cutter-heads R R are supported in a pendent manner from above, and are free to approach or recede from each other below, whereby the curvilinear side recesses *d d* are cut in the strip. When a like configuration or hollow is required on both sides of the strip, a single revolving cam, A', operating against pins *d' d'* on the sliding lower bearings *a' a'*, suffices; but when a different configuration is required on the one side of the strip, as compared with the other, then each sliding lower bearing may be operated by a separate cam of suitable shape. Said cam A' simply serves to force the horizontal cutter-heads R R apart, the latter, or their lower sliding bearings, being drawn together or made to follow up the cam by means of the pendent support of said cutter-heads, in combination with a certain arrangement of the belt by which they are rotated,

thereby dispensing with weights or springs to operate conjointly with the cam. Said cam A' has its rotary motion given to it by a spur-wheel, *s'*, in gear with the wheel *r*, bevel-pinions *e' f'*, and a train of gearing, *h' i' j'*.

The rotary motion of the cutter-heads R R is produced by a belt, as follows: B' is a vertical shaft, which is revolved by a belt, *k'*, and pulleys from the driving-shaft F. On the upper end of this vertical shaft B' is a pulley, *l'*, round which the belt *m'*, that rotates the cutter-heads R R, is passed. This belt passes from the pulley *l'* on the off side of the machine to and round a tension-pulley, *n'*, upon the other side of the machine or opposite side of the combined cutter-heads, from thence back to and around a pulley, *r¹*, on the shaft of the cutter-head R, furthest from the tension-pulley *n'*, and from thence to and around a pulley, *r²*, on the shaft of the other cutter-head R, from whence it passes back to the pulley *l'*. By this arrangement of the belt *m'* the cutter-heads R R are drawn together or held up to their lateral reciprocating action by the cam A' through or by the same belt which serves to rotate them, with provision, however, for yield of the belt to allow of said cutter-heads being forced apart by the cam A' without endangering the subsequent slip of the belt.

What is here claimed, and desired to be secured by Letters Patent, is—

1. The cutter-head D, having a threefold motion, as described, namely, a revolving one over the stuff or strip to be worked, a reciprocating lateral one relatively to said strip, and a reciprocating up-and-down motion in relation thereto, when constructed substantially as specified.

2. The combination of the sliding or laterally-moving bearing-box G and its cam H with the rocking bearing *v*, the revolving cutter-head shaft E, the rising-and-falling front bearing Q, and the cam P, essentially as and for the purposes herein set forth.

3. The pendent revolving cutter-heads R R, in combination with one or more intermediate cam or cams, A', the driving-belt *m'*, and the pulleys *l' n'* and *r¹ r²*, when the whole are arranged for operation substantially as specified.
